Primary Examiner — Adam C Mager*(74) Attorney, Agent, or Firm* — Shumaker, Loop & Kendrick, LLP; S. Alexander Long, Jr.(57) **CLAIM**

The ornamental design for a vehicle wheel rim, as shown and described.

DESCRIPTION

FIG. 1 is a perspective view of the new design for a vehicle wheel rim; and,

FIG. 2 is a front view thereof.

The dashed broken lines in the drawings depict environmental subject matter that forms no part of the claimed design; the dot-dash lines represent unclaimed boundaries and form no part of the claimed design.
